VANITY CASE

Winfred T. Parkin, Providence, R. I., assignor to
Theodore W. Foster & Bro. Company, Providence, R. I., a corporation of Maine

Application May 27, 1935, Serial No. 23,586

15 Claims. (Cl. 132—82)

This invention relates to powder containers such, for example, as vanity cases and like articles.

The principal objects of the invention are to provide a vanity case or like article having a powder compartment provided with inner and outer covers each having catches successively operable by means of a single finger piece; to provide a vanity case having inner and outer covers which are so constructed and arranged that the inner cover may be swung to closed position by the outer cover, and having a double-acting finger piece operable first to release the outer cover and then the inner cover; and to provide a vanity case having a substantially leakproof construction, which is compact and of pleasing and attractive appearance, which is of strong and durable construction having but few parts, which is inexpensive to manufacture and easy to assemble, and which can be sold at a relatively low cost.

Further objects and advantages will be apparent from a consideration of the following description and accompanying drawing, wherein:

Fig. 1 is a perspective view of a vanity case constructed in accordance with the present invention;

Fig. 2 is an enlarged section, with parts broken away, on the line 2—2 of Fig. 1;

Fig. 3 is an enlarged section, with parts broken away, on the line 3—3 of Fig. 1, looking in the direction of the arrows;

Fig. 4 is a fragmentary top plan view, with parts broken away and shown in section, showing the double-acting latch mechanism and associated parts when both catches are in locking position;

Fig. 5 is a view similar to Fig. 4, but showing the position of the parts when only the catch for the outer cover is released;

Fig. 6 is a view similar to Figs. 4 and 5, but showing the position of the parts when the catches for both the inner and outer covers are released; and

Fig. 7 is a perspective view of the catches and finger piece.

The embodiment chosen for the purpose of illustration comprises a casing 1 which may be of any desired size and shape, here shown as being circular in plan view and having a convex bottom wall 2 which is integral with its curved upstanding side wall 3. The parts are preferably of sheet metal or other suitable material which may be easily shaped or worked and which is capable of receiving and retaining a good sur-

face finish. A hinge 4 supports an outer cover 5 which carries a downwardly and inwardly curved tongue or lip 6 and, if desired, a mirror 7 may be built in or otherwise secured to the cover 5 in any suitable manner. As here shown, the mirror 7 is held in place by an annular flange 8 having on its inner periphery a bead 9 spaced from the outer periphery of the cover. A nose 10 is soldered or otherwise secured to the bead 9 at a point intermediate the lip 6 and hinge 4, the bead 9 and nose 10 constituting, in effect, a cam element, the utility of which is hereinafter described.

Mounted within the casing 1 is a powder tray 12 (Figs. 2 and 3) having a curved bottom wall 14 16 which rests on the bottom wall of the casing and an upstanding side wall which terminates in a shouldered rim 15 having an upstanding peripheral flange 16 which engages the inner surface of the overhanging upper edge of the side 20 wall of the casing, as shown in Figs. 2 and 3, thus firmly securing the tray within the casing. The hinge 4 is preferably secured to the upper edge of the flange 16, although it is to be understood that the hinge may be attached directly to the 25 casing 1.

The shouldered rim 15 is provided with an opening 18 (Figs. 1 and 4 to 6) and at a point diametrically opposite the opening 18 the rim 15 is provided with spaced radially extending 30 slits, and between these slits the rim is bent downwardly and the adjacent portions are bent upwardly so as to provide a pair of spaced hinge sockets 20 (Fig. 1). At a point diametrically opposite the hinge 4, a slot or recess 21 is formed 35 in the flange 16 (Fig. 2) to receive the tongue 6 of the outer cover, and a correspondingly located portion of the wall 3 of the casing is provided with a slot 22 (Figs. 4 to 6) and a notch 23 (Fig. 1).

The inner cover or closure member 25 is formed with a radially extending bifurcated tongue which is bent, curled or otherwise shaped to provide hinge sockets 26, and a small coil spring 27 is interposed between the hinge sockets 26, as shown in Figs. 1 and 3. A pintle 28 extends through the coil spring 27 and the sockets 20 and 26 and thus provides a pivotal support for the cover 25. The ends of the coil spring 27 act against the adjacent edge of the cover 25 and the rim 15, respectively, and normally urge the cover toward open position. The tray 12 provides an inner compartment for the reception of powder and the cover 25 provides a bottom 55

wall of an outer compartment located between the inner and outer covers.

Where, as here shown, the tray 12 is designed to hold loose powder, the inner cover 25 may be provided with a seal or gasket, and to this end a layer of compressible packing material 30 is clamped in place by means of a plate 31 which is secured to the body of the cover 25 by a rivet 32 (Fig. 1). When the cover 25 is in closed position, as shown in Figs. 1 to 3, the fibrous packing material is under sufficient compression to provide a leak-proof seal about the shouldered rim of the tray, and when the cover 25 is opened, as shown by the broken lines in Fig. 2, its rim engages the bead 9 on the inner surface of the outer cover. These parts are so constructed and arranged that when the outer cover is being swung to closed position, the bead 9 engages the rim of the cover 25 and acts as a cam element to effect the closing of the inner cover. The effective length of the bead 9 which performs this function includes the nose 10 which projects outwardly from the bead 9 a distance sufficient to effect the complete closing of the inner cover when the outer cover is in fully closed position, as shown in Fig. 3.

The inner and outer covers are held in closed position by a releasable locking mechanism which is normally operative to hold the covers in closed position and which is operable by a single finger piece to effect the successive release of the covers. As here shown by way of example, this mechanism comprises a resilient member 35 (Fig. 7) formed from a single piece of sheet metal or like inherently resilient material and this resilient member is shaped to provide a flexuous element having a bow-like or substantially U-shaped part consisting of legs 36 and 37 and an intermediate part 38, and a hooked extension or arm 39 adjoining the leg 37. A catch 40, having an outwardly extending lip 41 is formed on the intermediate part 38 and a similar catch 42 having an inwardly extending lip 43 is formed on the arm 39. A finger piece 45, either formed integral with or secured in any suitable manner to the part 38, is shaped to fit the slot 22 in the wall 3 of the casing, and the catches 40 and 42 are shaped to fit the notches 21 and 23 in the flange 16 and wall 5, and the opening 18 in the rim 15, respectively. These parts are so constructed and arranged that when assembled with the casing and tray, the catch 40 projects through the notches 21 and 23 with its lip 41 normally positioned to engage the lip 6 of the cover; the catch 42 projects through the opening 18 with its retaining lip normally overlying the upright wall of the tray so as to engage the edge of the cover 25; the finger piece 45 projects through the slot 22 with its end exposed on the outside of the casing; and the ends of the legs 36 and 37 yieldingly engage the curved surface of the upright wall of the tray and the ends of the intermediate part 38 abut the inner wall 3, and thus hold the parts in the position shown in Fig. 4, wherein both catches are held in locking position.

When the finger piece 45 is pressed inwardly from its normal position (Fig. 4) to the initial position (Fig. 5), the legs 36 and 37 first spread apart a slight distance (as shown by a comparison of Figs. 4 and 5) which is sufficient to allow the catch 40 to move inwardly a distance sufficient for its lip 41 to become disengaged from the lip 6, thus releasing the outer cover 5 and permitting it to be swung open. During this

initial movement the arm 39 and catch 42 have undergone a very slight counter-clockwise movement which is insufficient to disturb the engagement between the lip 43 and the rim of the cover 25. A further inward movement of the finger piece from the position shown in Fig. 5 to final position (Fig. 6) not only tends to spread the legs 36 and 37 still further apart, but causes the leg 37 to act as a lever which swings the arm 39 and catch 42 outwardly away from the edge 10 of the inner cover (as shown by a comparison of Figs. 5 and 6) into the position shown in Fig. 6, wherein the lip 43 is disengaged from the edge of the cover 25, thus permitting the cover to swing open by the action of the spring 37. When the pressure on the finger piece is released, the inherent resiliency of the legs 36 and 37 effect the return of the parts to normal position (Fig. 4).

While I have shown and described one desirable embodiment of the invention, it is to be understood that this disclosure is for the purpose of illustration only and that various changes in shape, proportion and arrangement of parts, as well as the substitution of equivalent elements 25 for those herein shown and described, may be made without departing from the spirit and scope of the invention as set forth in the appended claims.

I claim:

1. A casing comprising hinged inner and outer covers, a movable member disposed on the inside of the casing and movable from a normal position to an extended position, a pair of catches mounted on said movable member and operative 35 when said movable member is in normal position to hold the covers in closed position, and a single finger piece associated with said movable member and operative to move said movable member to extended position, thereby to effect the successive release of said catches.

2. A casing comprising hinged inner and outer covers, a movable member disposed on the inside of the casing and movable from a normal position to an extended position, a pair of catches 45 mounted on said movable member and operative when said movable member is in normal position to hold the covers in closed position, and a finger piece associated with said movable member and operative to move said movable member to 50 extended position, thereby first to release the catch for the outer cover and then the catch for the inner cover.

3. A casing comprising hinged inner and outer covers, a movable member disposed on the inside of the casing and movable from a normal position to an extended position, a pair of catches mounted on said movable member and operative when said movable member is in normal position to hold the covers in closed position, and 60 depressible means exposed on the outside of said casing and connected to said movable member, said depressible means being operative to move said movable member to extended position, thereby releasing said catches.

4. A casing comprising an inner compartment, a hinged inner cover closing said inner compartment, a hinged outer cover closing an outer compartment formed between the inner and outer covers, a movable member interposed between the inner and outer compartments and movable from a normal position to an extended position, a catch for releasably locking the inner cover in closed position, a catch for releasably locking the outer cover in closed position.

tion, each catch being mounted on said movable member and operative to release the covers when said movable member is moved to extended position and a finger piece connected to said movable member and operative to move said movable member to extended position, thereby to effect the release of said catches.

5. A casing comprising an inner compartment, a hinged inner cover closing said inner compartment, a hinged outer cover closing an outer compartment formed between the inner and outer covers, a movable member interposed between the inner and outer compartments and movable from a normal position to an extended position, 10 releasable catches mounted on said movable member and operative to hold the inner and outer covers in closed position when said movable member is in normal position, and a depressible finger piece exposed on the outside of 15 said casing and associated with said movable member for successively releasing first the catch for the outer cover and then the catch for the inner cover.

6. An article of the class described comprising 20 a casing, a hinged outer cover, a movable member disposed on the inside of the casing and movable from a normal position to an extended position, a catch for holding the outer cover in closed position, said catch being mounted on said movable member and movable inwardly to release the outer cover, a hinged inner cover, a catch for holding the inner cover in closed position, the second catch being mounted on said movable member and movable outwardly to release the inner cover, and a single finger piece 25 for moving said movable member so as to move the first catch inwardly and the second catch outwardly.

7. An article of the class described comprising 30 a casing, a hinged outer cover, a movable member disposed on the inside of the casing and movable from a normal position to an extended position, a catch for holding the outer cover in closed position, said catch being mounted on said movable member and movable inwardly to release the outer cover, a hinged inner cover, a catch for holding the inner cover in closed position, the second catch being mounted on said movable member and movable outwardly to release the inner cover, and a single depressible 35 finger piece exposed on the outside of the casing for releasing both catches, said catch being so connected to said movable member that the initial depression of the finger piece will release the first catch and further depression of the finger piece will release the second catch.

8. An article of the class described comprising 40 a casing having a cover and a releasable catch for holding it in closed position, a tray within the casing, a cover for said tray and a releasable catch for holding it in closed position, a resilient member supporting the catches in locking position and means connected to said resilient member for flexing it in such a manner as to 45 effect the release of first the cover of the casing and then the cover of the tray.

9. An article of the class described comprising 50 a casing, an outer cover for said casing, a powder tray within said casing, an inner cover for said tray, and releasable means for locking the inner and outer covers in closed position, said means comprising a resilient member interposed between said tray and casing, catches mounted on said resilient member and engageable with said covers, said resilient member normally holding said

catches in position to engage said covers, and a depressible finger piece operative to flex said resilient member, thereby successively to release first said catch for said inner cover and then the catch for the outer cover.

5

10. An article of the class described comprising 10 a casing, an outer cover for said casing, a powder tray disposed within said casing, an inner cover for said tray, and releasable means for locking the inner and outer covers in closed position, said means comprising a resilient member interposed between said tray and casing, catches mounted on said resilient member and engageable with said inner and outer covers, said resilient member normally holding said catches in position 15 to engage said covers, and a depressible finger piece having a part exposed on the outside of said casing and operative to flex said resilient member, thereby successively to release said catches.

11. An article of the class described comprising 20 a casing, an outer cover for said casing, a powder tray disposed within said casing, an inner cover for said tray, and releasable means for locking the covers in closed position, said means comprising a resilient member interposed between 25 said tray and casing, a pair of catches carried by said member and normally held in a position to engage said covers to hold them in closed position, and a finger piece operative to depress a part of said member and cause a successive movement of said catches relative to said tray and casing, thereby to effect the successive release of 30 said catches.

12. An article of the class described comprising 35 a casing, an outer cover for said casing, a powder tray disposed within said casing, an inner cover for said tray, and releasable means for locking the covers in closed position, said means comprising a pair of releasable catches engageable with said covers to lock them in closed position, a resilient 40 member interposed between said tray and casing, said resilient member supporting and acting on said catches normally to hold them in locking position, and a finger piece connected to said resilient member intermediate its ends, whereby depression of said finger piece effects the release of 45 said catches.

13. An article of the class described comprising 50 a casing, an outer cover for said casing, a powder tray disposed within said casing, an inner cover for said tray, and releasable means for locking the covers in closed position, said means comprising an arcuate shaped resilient member interposed between said tray and casing, a catch carried by 55 said member intermediate its ends and normally engageable with said outer cover to hold it in closed position, a second catch carried by said member and normally positioned to engage said inner cover to hold it in closed position, and a finger piece secured to said member and operative when depressed to effect first the release of 60 the first catch and then the release of said second catch.

14. An article of the class described comprising 65 a casing, an outer cover for said casing having an inturned lip, a powder tray disposed within said casing, an inner cover for said tray, and releasable means for locking the covers in closed position, said means comprising a catch movable 70 from a locking position, wherein it engages said lip to hold said outer cover closed, inwardly to a position where it is clear of said lip, a second catch movable from a locking position, wherein it engages the inner cover, outwardly to a position 75

clear of said cover, a resilient member interposed between said tray and casing and supporting said catches normally to hold them in locking position, and a depressible finger piece connected to said member intermediate its ends, so that depression of said finger piece first effects the inward movement of the first catch to release the outer cover and then the outward movement of the second catch to release the inner cover.

10 15. A casing comprising inner and outer covers

hinged to said casing at spaced points, the inner surface of the outer cover having an arcuate beaded portion adjacent to its periphery and a nose constituting a cam element engageable with the rim of the inner cover and operative to swing it to closed position, and releasable catches operative to lock said covers when swung to closed position.

WINFRED T. PARKIN. 10
